Patented Jan. 20, 1920.

INVENTOR
IGNACY STYNKOWIC
BY *Adam E. Schatz*
ATTORNEY

UNITED STATES PATENT OFFICE.

IGNACY STYNKOWIC, OF EAST HAMMOND, INDIANA.

COMBINED FOLDING CHAIR AND TABLE.

1,328,462.

Specification of Letters Patent. Patented Jan. 20, 1920.

Application filed May 7, 1919. Serial No. 295,405.

To all whom it may concern:

Be it known that I, IGNACY STYNKOWIC, a citizen of the United States, residing at East Hammond, county of Lake, and State of Indiana, have invented certain new and useful Improvements in Combined Folding Chairs, and Tables, of which the following is a specification.

This invention relates to improvements in articles of furniture and particularly to tables and chairs used in connection therewith.

The principal object of the invention is to provide a table to which are attached upon each of its sides, chairs so arranged that they may be folded and deposited below the table surface when not in use, in a simple and easy manner.

These and other like objects are attained by the novel construction and combination of parts hereinafter described, and shown in the accompanying drawings, forming a material part of this disclosure, and in which:—

Figure 1 is a top plan view showing an article of furniture made in accordance with the invention, and

Fig. 2 is a side elevational view of the same, some of the chairs being extended, others partially folded, and still others shown folded below the table top.

Referring to the drawings, the numeral 10 designates a rectangular table top supported at its corners upon posts or legs 11, secured so as to stand rigidly by longitudinally disposed bars 12, and cross bars 13, while immediately below the top or cover 10 at each side, are secured shelving elements 14, having partitions 16. Transverse elements 16 extend below the table top and secured upon their outer edges are plates 18.

Pivoted in each of the pairs of legs, are bars 20 and 21, respectively at the ends and sides, and rigidly engaged with the bars 45 are the inner edges of platform 22, having upon their lower side a pivoted strip carrying feet 23, adapted to make contact upon the surface on which the table 11 stands.

Upon the upper surface of the platforms 22 50 are pivotally secured standards 24, held by nuts 25, or like securing means, on their lower ends.

The upper ends of these standards are engaged with chair seats 27, provided at 55 their outer rear corners with pairs of rigid legs 28.

Hingedly engaged upon the side of the chair seats 27, by pivots 29, are the chair backs 30, formed with integral connecting elements 31, and having secured upon their lower ends cleats 32, engageable with the extreme rear end of the chair seats 27 so as to hold the backs in a proper inclined position, but permitting the backs to be folded over the seats in an obvious manner.

Thus each of the chairs may be pivoted upon a single front support 24, so as to permit a person to conveniently make use of the chair when the same is in an outward extended position, as shown at the left hand of Figs. 1 and 2. When any of the chairs is not desired for use, the backs 30 are folded over the seat, the platforms 22 raised upon the pivotal bars 20, and swung under the table top 10, as shown in the dotted lines in Figs. 1 and 2.

In order to secure the chair elements when in a folded position, the strips carrying the feet 23 are turned outwardly, said strips engaging clips 34, fixed upon the outer surface of the longitudinal plates 18, thereby holding the chairs in a folded position.

From the foregoing it will be seen that a table having combined with it permanent chairs has been disclosed, and that the chairs are adapted to be folded to extend below the table when not used, permitting the table to be used for any purpose which may be desired and accommodating either one or more people according to the number of chairs engaged therewith.

Having thus described my invention what I claim as new and desire to secure by Letters Patent, is:—

1. In a device of the class described, the combination with a table having four legs, of platforms hingedly engaged upon each side of said table, supports for said platforms, chairs arranged upon said platforms, said chairs each having a single pivoted front leg and a pair of rigid rear legs, and means for holding said chairs and platforms when in a folded position below the said table top.

2. In a table of the class described, the combination with a rectangular plate, legs rigidly engaged with said plate, platforms hingedly engaged at the lower portion of said legs, pivotal supports for said platforms adapted to rest upon the surface on which said table legs rest, chairs having a single front leg pivotally engaged in said

platforms, a pair of rigid legs extending downward from each of said chairs adapted to make contact with the upper surface of said platforms, backs pivotally engaged 5 with said chairs adapted to be folded thereover, means for holding said backs when in an extended position, and means for holding said platforms when in a folded position below said plate.

10 3. In a device of the class described, the combination with a rectangular top table, having legs rigidly engaged at each corner thereof, bars pivotally engaged between said legs at the sides and ends thereof, plat-

forms secured to said bars, supports pivot- 15 ally engaged below said platforms, chairs composed of seats and rigid rear legs adapted to rest on said platforms, a single front leg pivoted in said platforms, backs pivotally engaged with said chair seats, 20 means for preventing said backs from swinging rearwardly, and means for holding said platforms and chair elements below said table when in a folded position.

In testimony whereof I have affixed my 25 signature.

IGNACY STYNKOWIC.
